UNITED STATES PATENT OFFICE

133,556

DESIGN FOR A COMBINED FOLDER FOR BILLS, CHECKBOOK, AND CALENDAR

John P. Wege, West Bend, Wis., assignor to Amity Leather Products Co., West Bend, Wis., a corporation of Wisconsin

Application January 10, 1942, Serial No. 105,116

Term of patent 14 years

To all whom it may concern:

Be it known, that I, John P. Wege, a citizen of the United States, residing at West Bend, in the county of Washington and State of Wisconsin, have invented a new, original, and ornamental Design for a Combined Folder for Bills, Checkbook, and Calendar, of which the following is a specification, reference being had to the accompanying drawing, forming a part thereof, and in which:

The design appears wholly on the front of the article as best shown in Figs. 1 and 3, the reverse side being plain.

I claim:

The ornamental design for a combined folder for bills, checkbook, and calendar, as shown and described.

JOHN P. WEGE.
